UNITED STATES PATENT OFFICE

JOHN T. TRUMBLE, OF LANSING, MICHIGAN

ROTARY COMPRESSOR

Application filed December 19, 1927. Serial No. 240,886.

This invention relates to rotary compressors and pumps for handling gaseous fluids as in compression refrigeration apparatus.

It is an object of this invention to provide an improved form of rotary compressor, especially adapted for direct connection to electric motors to operate efficiently at the high speeds required by such connections. In order to accomplish efficient operation of the compressor, I have provided a form wherein the cylinder and piston rotate as a unit with the end seals so that the relative movement and consequently the wear in the pump is reduced to a minimum, thus resulting in long life. An advantage of my arrangement over the usual form of vane pump is that vane friction is eliminated, the full and uninterrupted bearing of the rotating cylinder being far less subject to wear.

It is also an object of this invention to provide a rotary compressor embodying improved self-adjusting end seals for the compression space.

It is another object of this invention to provide an improved and simplified rotary compressor that can be varied in capacity at slight cost by simply varying the diameter of the rotor and the eccentricity of the rotor shaft in the casing. To this end the bearings for the rotor shaft are formed as removable eccentric sleeves which may be replaced by externally similar sleeves having a different eccentricity in order that a variety of sizes of casings, etc. may be replaced by a single standard casing.

Other and further important objects of this invention will be apparent from the disclosures in the specification and the accompanying drawings.

This invention (in a preferred form) is illustrated in the drawings and hereinafter more fully described.

On the drawings:

Figure 1 is a horizontal section through a compressor embodying the features of this invention, this section being an enlarged representation on the line I—I of Figure 2.

Figure 2 is a vertical cross section of the compressor taken on the line II—II of Figure 1 on a reduced scale.

As shown on the drawings:

A cylindrical casing 10 is provided with cooling fins 11 and suitable mounting feet 12, the casing having a simple cylindrical bore 13 with offset oppositely disposed inlet 55 and outlet connections 14 and 15 in the wall thereof. Each end of the bore is closed by substantially similar end covers 16 bolted to the casing and having centrally apertured boxes 17 thereon aligned with the axis of the 60 cylindrical bore 13. Cylindrical sleeve bearing shells 18 and 19 are mounted in the bosses 17, the sleeve 18 being an end bearing, so that the boss 17 therefor is sealed by a plug 20, while the sleeve 19 is extended beyond the 65 end of the other cover boss and is formed to receive packing 21 and a packing nut 22.

The sleeve bearing shells 18 and 19 are intended to be readily replaceable and are formed with eccentric shaft apertures 23 for 70 a shaft 24, it being an object of this invention to provide a series of such sleeve bearing shells with varying eccentricity of the shaft bearings to vary the displacement volume of the compressor.

The shaft carries a concentric rotor 25 secured thereon, this rotor being relieved at the sides adjacent the sleeves to reduce friction and permit limited side play. The cylinder of the compressor proper is formed as 80 a shell 26 having a counterclockwise rotation in the casing bore 13, and a groove 27 is formed thereon over part of the outer surface in alignment with the outlet connection 15. This groove communicates with the interior of the shell through an outlet port 28 and a similar port 29 and groove 29a offset from the port 28 and its groove 27 forms the suction or inlet connection from the suction space between the rotor 25 and the shell 26. 90 The shell is purposely made wider than the rotor to provide for end sealing discs 30 having peripheral flanges 31 bearing against the inside of the shell 26. These discs also have flanges 32 journaled on inward extensions 33 on the sleeve bearing shells 18 and 19 which are concentric with the cylinder. The cylinder is yieldingly maintained in alignment with the rotor and the end seals are simultaneously urged against the rotor 100

by means of lugs 34 and springs 35 beneath the heads of bolts 36 passing through clearance apertures 37 in the rotor.

The cylinder 26 is rotated by the rotor 25 by means of a partition blade 38 which has a rocker-like bearing 39 in the inner surface of the cylinder and slides between semi-circular bearings 40 in the rotor.

It will be evident from the foregoing description that by increasing the eccentricity of the shaft bearings in the sleeves 18 and 19 and simultaneously decreasing the diameter of the rotor, the capacity of the compression space will be increased and vice versa. Thus, 15 the same casing, cylinder, end seals and shaft can be used in a series of compressions of different capacities with a material saving in expense of inventory manufacture. This feature is of special importance in domestic 20 refrigeration apparatus wherein varying capacities are required.

In the normal operation of the compressor of this invention the rotor and cylinder rotate counterclockwise together about eccentric but fixed axes, the point of tangency between the rotor and cylinder remaining fixed although the actual points in contact shift over the whole surfaces of the moving members. Thus in Figure 2, the crescent shaped 25 space to the left of the vane is decreasing in area at the same time as it shifts around towards the point of tangency adjacent the lead line 24. When the vane location passes the point of tangency a new cycle is started, fluid 30 being drawn in back of the vane through the port 29, while a previous charge is being compressed ahead of the vane. The fluid drawn in back of the blade is transferred to the front thereof by the movement of the 35 vane past the point of tangency of the eccentric cylinder and rotor. The spring urged end plates 30 serve to take up wear and also act as relief valves should excessive pressures develop due to the admission of slugs 40 of liquid.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A rotary compressor comprising a casing, a cylindrical shell rotatable therein, end closures for said casing, a shaft eccentrically journalled in said end closures, a rotor on said shaft within said shell, a partition blade connecting said shell to said rotor and end seals yieldingly and slidingly attached to said rotor and contacting said shell.

2. A rotary compressor comprising a casing, a cylindrical shell rotatable therein, end closures for said casing, a shaft eccentrically journalled in said end closures, a rotor on

said shaft within said shell, a partition blade connecting said shell to said rotor, and end seals on either end of the rotor having a bearing inside said shell.

3. A rotary compressor comprising a cylinder, a shaft eccentric thereto, a rotor on said shaft, a partition blade connecting said cylinder to said rotor, and end seals yieldingly and slidingly attached to said rotor and contacting said shell. 70 75

4. A rotary compressor comprising a cylinder, a shaft eccentric thereto, a rotor on said shaft, a partition blade connecting said cylinder to said rotor, and end seals on either end of the rotor having a bearing inside said shell. 80

5. A rotary compressor comprising a casing, a cylindrical shell rotatable therein, end closures for said casing, a shaft eccentrically journalled in said end closures, a rotor on said shaft within said shell, a partition blade connecting said shell to said rotor, end seals associated with said rotor having a bearing inside said shell, and means yieldingly urging said seals against said rotor. 85 90

6. A rotary compressor comprising a cylinder, a shaft eccentric thereto, a rotor on said shaft, a partition blade connecting said cylinder to said rotor, end seals on either end of the rotor having a bearing inside said cylinder, and means yieldingly urging said seals against said rotor. 95

In testimony whereof I have hereunto subscribed my name.
